(57) **CLAIM**

The ornamental design for the apparatus to suspend gloves for drying, as shown and described.

DESCRIPTION

FIG. 1 is a front elevational view of the apparatus to suspend gloves for drying;

FIG. 2 is a rear view thereof;

FIG. 3 is a right view thereof;

FIG. 4 is a left view thereof;

FIG. 5 is a top view thereof;

FIG. 6 is a bottom view thereof; and,

FIG. 7 is a perspective view of the apparatus to suspend gloves for drying in condition of use suspending a pair of gloves.

The broken lines are for environmental purposes only and form no part of the claimed design.
